William Robotham, of Newark, N.J.

DES. 1944

Assor to

Himself and Walter Greason, of the same place.

Letters Patent No. 1944-Dated May 10th 1864.

Design for a Trade Mark.

The schedule referred to in these Letters Patent and making part of the same.

Scale where it may concern:

Be it known that William Robotham, of Newark in the County of Essex and State of New Jersey, have invented or produced a new and original design for a Trade Mark for Carriage and Harness Ornaments; and I do hereby declare that the following is a full, clear and exact description of the same, reference being had to the accompanying drawing which forms a part of this specification.

This trade mark is placed on the exterior of the packages in which the articles or goods are done up and the design consists in having a rectangular label printed with a red ground a, and bounded by a dark narrow stripe b. Centrally within the red ground a, there are two concentric elliptical dark and white stripes c, c, with a space between them sufficiently wide to admit of the title of the goods being expressed in letters of prominent size, as, "Fine Silver Rosettes", the latter word "Rosettes" is not constant, it being changed according to the kind of goods enclosed in the package.

At the centre of the smaller elliptical stripe, c, there is a ring d, of dark color on which is lettered, "Original Manufacturers of red label goods."

The space e, included between the inner elliptical stripe c, and the ring d, is ornamented with what is commonly termed engine work, and at the centre of the ring d, there is a circular plain red ground f, in which the

2. The monogram R. & G. is engraved or printed, the space between the interior of the ring d. and the red circle f. is ornamented with fine "engine work."

Having thus described my invention, what I claim as new and desire to secure by Letters Patent is.

The within described Trade mark or label, composed of the red ground, engine ornamented work and lettering as herein set forth.
